UNITED STATES PATENT OFFICE.

JAMES V. WASHBURN, OF SYRACUSE, NEW YORK.

INK-WELL.

1,134,429.

Specification of Letters Patent.

Patented Apr. 6, 1915.

Application filed February 6, 1911, Serial No. 606,840. Renewed September 4, 1914. Serial No. 860,302.

To all whom it may concern:

Be it known that I, JAMES V. WASHBURN, of Syracuse, in the county of Onondaga, in the State of New York, have invented new and useful Improvements in Ink-Wells, of which the following, taken in connection with the accompanying drawings, is a full, clear, and exact description.

This invention relates to certain improvements in ink wells involving the use of a cup-shape base section and an inverted reservoir or bottle section containing a reserve quantity of ink adapted to automatically feed into the base section as the supply in the latter recedes below a predetermined level normally sealing the opening in the bottom of the reservoir to prevent the entrance of air thereto, both of said sections being provided with recesses in one side adapted to be brought into registration with each other by the relative rotation of one of the sections upon the other for the entrance of a pen or such recesses may be moved out of registration with each other by such relative rotation to effectively close the recess in the base and thereby prevent excessive evaporation of ink. In this particular form of ink well, the central portion of the ink reservoir in the base section is preferably elevated to form a pocket or pockets registering with the recess or recesses therein and at the same time forming abutments at the inner sides of the pocket limiting the entrance of pens into the reservoir, the pockets serving to retain at all times a sufficient depth of ink for ready use, while the remaining portions of the upper portion of the base form bearings for receiving and supporting the superposed bottle or main reservoir.

So far as I am aware the bearing surfaces between the bottle and base sections in devices of this character heretofore devised have always been substantially flat or of sufficient contact area to cause capillary attraction and consequent drying of the ink at this joint, thereby causing the sections to stick or adhere one to the other with sufficient resistance to prevent relative turning of said sections or removal of one from the other without liability of breakage. Furthermore the upper face of the raised center of the base section in devices of this character now in use is, so far as I know, substantially flat or concave which allows the ink to collect and dry thereon, especially

when the ink is exhausted from both sections.

My main object, therefore, is to avoid these objectionable conditions and to thereby keep both sections freer from accumulations of dried ink and at the same time permitting said sections to be rotated relatively to each other with the utmost freedom.

I am aware that it is common to employ spring tensioned arms or straps for detachably locking the sections of the ink well together but in all of the devices with which I am familiar, the bearing portions of the spring arm or straps upon the inverted bottle is comparatively narrow and contacts with the upper surface of the bottle throughout practically its entire diameter, thus producing excessive friction against rotation and allowing the bottle to be tilted transversely of the line of extension of the strap when the inner wall is lifted or moved up by means of the top section or bottle.

Another object, therefore, of my present invention is to provide the bottle retaining spring with a central circular bearing of comparatively broad area engaging in a circular recess in the top of the bottle coaxial with its axis of rotation, leaving the remaining portions of the spring free from engagement with said bottle and thereby permitting the latter to be rotated more freely relatively to the base section.

A further object is to provide the base of the well with one or more rotarily adjustable pen racks and to construct such base in such manner that these racks may be frictionally held in their adjusted positions.

Other objects and uses will be brought out in the following description:

In the drawings: Figures 1 and 2 are respectively a top plan and a side elevation of an ink well embodying the various features of my invention, portions of opposite sides of the well being shown in section in Fig. 2. Figs. 3 and 4 are respectively a transverse vertical sectional view of the well taken on line 3—3, Fig. 1 and a horizontal sectional view through the base taken on line 4—4 Fig. 2, Fig. 4 showing particularly the manner of frictionally holding the pen racks in their adjusted positions. Fig. 5 is a transverse vertical sectional view of the base taken at right angles to that shown in Fig. 3.

This ink well comprises a base section —1— and a superposed bottle section or

reservoir —2— rotatably mounted in an inverted position in the top of the base section —1— and held in operative position against accidental displacement by a spring clamp —3—, the base section being preferably polygonous in top plan and having the central portion of its periphery between the top and bottom reduced in diameter at —4— for the reception and retention of a plurality of, in this instance two, split-ring pen racks —5— which are preferably made of spring wire and tensioned so as to frictionally grip the periphery of the reduced portion of the base as clearly shown in Figs. 2 and 4.

The base section —1— and bottle section —2— are preferably made of glass although they may be made of any other non-corrodible or acid resisting material.

The outer surface or perimeter of the base is shown as octagonal with its lower and upper ends flaring downwardly and upwardly respectively from the reduced portion —4— so as to retain the pen racks —5— in close juxtaposition against accidental upward or downward displacement, each pen rack preferably consisting of a split-ring of spring wire adapted to be sprung over and upon the perimeter of the base and tensioned to frictionally grip such perimeter and at the same time to permit it to be adjusted rotatably by hand to bring its pen supporting ends to any convenient position, said ends being preferably offset laterally in parallel lines some distance apart equal to or slightly greater than the length of one side of the base and are curved downwardly and upwardly to form suitable seats for receiving and supporting pens, pencils and similar articles.

The intermediate portion —6— of each pen rack diametrically opposite to the pen supporting arms is substantially straight a distance corresponding to the length of one of the sides of the base so as to fit closely against such side, thereby additionally holding the pen rack against accidental rotary displacement and at the same time permitting the entire pen rack to be adjusted rotatably by hand when necessary to bring the pen supporting arms to the desired position with the straight portion —6— in contact with one of the sides of the base.

The interior of the base is divided horizontally between its lower and upper sides by a partition or bottom wall —7— forming lower and upper chambers —8— and —9—, the lower chamber being simply for the purpose of reducing the weight of the base and its outer walls follow the general contour of the outer perimeter forming an octagonal supporting flange —10— having a substantially flat lower face except that it is provided at intervals with recesses —11— to permit the entrance of air and

thus preventing in a measure adhesion of the base to its support.

The upper chamber —9— is preferably circular and of slightly greater diameter than the base of the inverted bottle —2— which it is adapted to receive, thus forming a marginal flange —12— for retaining the bottle against radial displacement when mounted upon the base.

The partition or bottom wall —7— is preferably formed integral with the sides of the base —1— and consists of opposite nearly semi-circular inwardly projecting ledges —13— and a depressed diametrically extending portion —14— connected to the inner edges of the ledges —13— by upwardly flaring walls —15— forming a well —16—. The opposite ends of the depressed portion —14— are deflected downwardly and then upwardly and integrally united to the sides of the base —1—, thereby forming opposite ink pockets —17— for the reception of a pen, the inner sides of each forming abutments —18— to limit the inward movement of the pen into the well, it being understood that the well —16— and pockets —17— are open at the top for communication with the upper chamber —9—. The upper surface of the central portion of the depression —14— is therefore raised above the bottom of the pockets —17— and is rounded or convexed longitudinally to cause any accumulations of ink thereon to readily flow laterally into the pockets, thereby preventing any excessive quantity of ink from drying upon such surface in case its level should fall below this surface. The upper surfaces of the ledges —13— also incline downwardly and inwardly to prevent accumulation of ink thereon, such ink flowing readily into the well —16— thereby preventing in a measure adhesion between such surfaces and adjacent portions of the superposed bottle —2— resting thereon.

In order to prevent capillary attraction between the contiguous faces of the bottle and base, the upper surfaces of the ledges are provided with comparatively small integral knobs or ribs —19— spaced apart at suitable intervals and upon which the underside of the bottle —2— rests when in operative position thereby leaving the intervening space between the ledges —13— and underside of the bottle sufficient to prevent such bottle from adhering to the ledges. This bottle is provided in its lower side with a central neck —21— and opening —22— dipping into the well —16— directly over the central portion of the partition —14—, the distance between the horizontal plane of the portion of the bottle resting on the projections —19— and that of the lower end of the neck being slightly less than the corresponding distance to the top of the central portion of the partition —14— so as to leave an

intervening clearance between said partition and lower end of the neck of the bottle sufficient to permit the outflow of the ink from said bottle into the pocket —17— when adjusted for use.

One side of the bottle is depressed inwardly at —23— extending inwardly from the periphery and adapted to be moved into and out of registration with either one of the pockets —17— as the bottle is rotated so as to form a continuation of the pocket for the reception of a pen in dipping it into the well or when moved out of registration with the pockets overlies the ledges —13— while the bottom of the bottle effectively covers the upper open sides of the pockets —17— to exclude dust and prevent excessive evaporation of the ink.

The upper side of the bottle is provided with a central circular depression —24— in which is fitted a circular disk —25— having oppositely projecting spring arms —26— rising therefrom in abrupt turns clear from the bottle and extending downwardly along the sides thereof and having their lower ends terminating in inwardly projecting shoulders —27— for entrance into suitable recesses —28— in the adjacent sides of the base and against superposed shoulders —29— which effectively hold the bottle against accidental upward displacement from the base.

The spring arms —26— are preferably formed integral with the central disk —25— which is of considerably larger diameter than the width of the arms thereby affording a broad bearing which is held to the seat —24— under the spring tension of the arms —26— and serves to hold the bottle with greater firmness in operative position against lateral tilting movement and at the same time permitting said bottle to be rotated more freely on the base than would be possible if the arms —3— were in contact with the sides of the bottle. The object therefore in deflecting the arms forwardly in sharp bends from diametrically opposite sides of the disk is to free said arms from engagement with the bottle so that the main element operating to hold the bottle in operative position is the circular disk —24— which by reason of its being seated in a circular depression in the top of the bottle yieldingly but firmly holds the latter against lateral movement and also against tilting.

It will be observed upon reference to Fig. 5 that the opposite sides of the base —1— with which the adjacent ends of the spring arms —26— are engaged are recessed at —30— a sufficient depth to enable said arms to spring inwardly into said recesses and

within the perimeter of the corresponding portion of the base when interlocked with the shoulders —29— thereby protecting these ends of the springs as far as possible against accidental displacement from said shoulders. 65

What I claim is:

1. An ink well comprising a hollow base, a diametrically extending portion of the bottom wall thereof depressed and the ends 70 of the depressed portion still further depressed below its intermediate portion to form diametrically opposite ink pockets, an inverted bottle resting on the base and having an outlet directly over said intermediate 75 portion and a portion of the side wall of said bottle depressed to form a channel adapted to be brought into registration with either of said pockets.

2. An ink well comprising a hollow base 80 having ink pockets in its bottom at opposite sides of its center and the upper face of its central portion convex so as to incline from the center toward the pockets, and an inverted ink bottle resting on the top of the 85 base and having an outlet directly over the center of the bottom of said base.

3. An ink well comprising a base having a diametrically extending channel in its bottom, the ends of said channel being depressed below the center to form diametrically opposite ink pockets, the portions of the base at opposite sides of the channel being inclined toward the channel, an edge 90 flange extending upwardly from said base, 95 and an inverted bottle resting upon the top of the base and within said edge flange and rotatable with respect to said base and having its outlet registering with the intermediate portion of the channel between the 100 pockets.

4. An ink well comprising a hollow base having its bottom provided with a diametrically extending channel, the ends of 105 which are depressed below the central portion to form diametrically opposite ink pockets, the portions of the bottom of the base at opposite sides of the channel being inclined toward said channel and having raised portions, and an inverted ink bottle 110 resting on said raised portions and having an outlet registering with the intermediate portion of the channel between said pockets.

In witness whereof I have hereunto set my hand on this 3rd day of February 1911. 115

JAS. V. WASHBURN.
